Primary Examiner — Elizabeth Albert

(74) Attorney, Agent, or Firm — Larson & Larson, P.A.; Frank Liebenow; Justin P. Miller

(57) CLAIM

I claim the ornamental design for a desktop golf ball, as shown and described.

DESCRIPTION

FIG. 1 is a right side view of the desktop golf ball showing my new design;

FIG. 2 is a left side view thereof;

FIG. 3 is a rear elevation view thereof;

FIG. 4 is a front elevation view thereof;

FIG. 5 is a top plan view thereof; and,

FIG. 6 is a bottom plan view thereof.
